UNITED STATES PATENT OFFICE.

GEORGE H. DAWSON, OF BOSTON, MASSACHUSETTS, ASSIGNOR TO SERVICE BUREAU, INC., OF CAMBRIDGE, MASSACHUSETTS, A CORPORATION OF MASSACHUSETTS.

INDEX GUIDE CARD.

Application filed January 25, 1928. Serial No. 249,433.

This invention relates to index cards and particularly to guide cards provided with a projecting tab having a transparent covering adapted to receive a removable index slip and adapted for use in a vertical filing system to separate the cards, folders or other index matter constituting the filing system.

The principal object of the invention is to provide a guide card of simple and economical construction, the card having a projecting tab reinforced and protected by a sheath of transparent material constructed and arranged to permit the insertion and removal of an index slip or label.

15 A preferred embodiment of the invention is illustrated in the accompanying drawings, in which:

Fig. 1 is a front elevation of the improved guide card;

20 Fig. 2 is a rear view of said card;

Fig. 3 is an enlarged transverse section on the line 3—3 of Fig. 1; and

25 Fig. 4 is a view similar to Fig. 1 illustrating a type of connected index slips which may be employed with the improved tab.

The card body 5 may be made of any suitably stiff sheet material, such as cardboard, fiberboard or stout paper, and has an integral projecting tab 6 and a cover sheet 30 or sheath of transparent material, such as celluloid, which is folded over the top edge of the tab at 7 to provide front and rear flaps 8 and 9, respectively. The vertical edges and shoulders of the sheath prefer- 35 ably register with the edges of the card tab, to protect the card from wear. The rear flap 9 is fastened to the back face of the card and card tab by a suitable adhesive 10 which is applied over the entire surface of the flap 40 and securely unites the flap to the card.

The front flap 8 extends downwardly from the fold 7 over the face of the card tab and has its lower portion, which preferably reaches below the bottom edge of the rear flap 9, adhesively secured, as indicated at 12 (Fig. 3), to the card body, leaving the upper portion thereof free from the card surface to provide a label-receiving pocket. A slit 11, preferably extending longitudinally of 50 the card and spaced below the upper card edge at the bottom of said pocket, is provided in the flap 8 to permit the insertion and removal of the label; and small eyelets 14 are preferably provided through the free portion of the front flap, the card and the rear

flap to hold the margins of the pocket forming portion of the flap against the card and its tab, thereby to close the ends of the pocket and press said pocket-forming portion toward the card surface frictionally to hold 60 the label 15 within the pocket.

In order that the label may quickly and conveniently be inserted through the slit 11, the front flap 8 may, if desired, be formed with molded shoulders 13 disposed adjacent 65 the ends of the slit which tend to hold the mouth of the pocket open. While the eyelets 14 will tend to depress the free portion of the flap 8, it will be found that the provision of such fastening means does not 70 appreciably flatten the raised shoulders or ribs 13 against the card surface. The celluloid will be bent toward the card frictionally to hold the label within the pocket; but the shoulders at the bottom of the free portion 75 will be preserved in the form of raised ribs.

The label 15 may readily be inserted through the slit 11 and pushed upwardly until its top edge approximately coincides with the upper edge of the card tab 6, thus permitting the use of a large label and afford- 80 ing better visibility of the index data inscribed thereon. The lower margin of the label lies flatwise upon the card surface with its lower edge protected from external contacts by the thickness of the celluloid at the bottom of the slit. Notches 16, 17 may be provided to permit the label to be removed by the fingers.

The label may be a unitary slip of paper, 85 or it may form part of an elongate strip of interconnected labels, as illustrated in Fig. 4, which shows a series of individual labels 18 connected at the perforated lines 19. The end label may be inserted in the sheath 90 pocket and may readily be torn from the adjacent section at the perforations.

An index guide card constructed as above described is economical to manufacture, durable in use and is attractive in appearance; 100 the transparent sheath reinforces the card tab and protects the tab and the adjacent card body from soilage and wear, and provides a smooth, rounded upper edge at the top of the tab which is agreeable to the touch of the user; and the construction of the label pocket permits the label to be inserted with ease, and to be pushed upwardly 105 to the top of the tab, and to be adjusted in the desired position by hand; yet by fric- 110

tional contact holds the label against accidental removal, and prevents the protrusion of the sides of the label from the pocket. It will be understood, however, that details 5 of structure may be varied without departing from the spirit of the invention as defined in the appended claims.

I claim:

1. An index card having an integral projecting tab and provided with a transparent sheath folded over the card tab to furnish front and rear flaps, the rear flap being secured upon the rear surface of the tab and the front flap having its upper portion free 15 from the tab surface to provide a label-receiving pocket and having between its upper and lower portions a horizontal slit adjacent the bottom of the pocket to permit a label to be inserted into said pocket, the 20 lower portion of the front flap being secured flatwise upon the card, so that the label will be frictionally retained between the card tab and said upper flap portion with its upper edge adjacent the upper edge 25 of the card tab.

2. An index device comprising a card having an integral tab projecting above the card body, a transparent sheath folded over the card tab to form front and rear flaps, the rear flap being secured upon the rear face of the tab and the front flap having its upper portion free from the tab surface to provide a label-receiving pocket and having a horizontal slit adjacent the bottom of 30 the pocket to permit the insertion of a label, the portion of said front flap below said slit being secured flatwise upon the card body, and means for fastening the margins 35 of the pocket-forming portion of the front flap to the card, whereby a label received within said pocket will be frictionally held between the card tab and said pocket-forming portion of the sheath.

3. An index device comprising a card having an integral tab projecting above the card body, a transparent sheath folded over the card tab to form front and rear flaps, the rear flap being secured upon the rear face of the tab and the front flap having 45 its upper portion free from the tab surface to provide a label-receiving pocket and having a horizontal slit adjacent the bottom of 50

the pocket to permit the insertion of a label, the portion of said front flap below said slit being secured flatwise upon the card body, and fasteners passing through the margins 55 of the pocket-forming upper portion of the front flap and through the card, whereby the ends of the pocket are closed and the label will be frictionally held between the 60 card tab and said pocket-forming portion of the sheath.

4. An index device comprising a card having an integral tab projecting above the card body, a transparent sheath folded over the card tab to form front and rear flaps, the rear flap being secured upon the rear face of the tab and the front flap having its upper portion free from the tab surface to provide a label-receiving pocket and having a horizontal slit adjacent the bottom of 65 the pocket to permit the insertion of a label, said slit being spaced below the upper edge of the card body, the portion of said front flap below said slit being secured flatwise upon the card body, and metal fasteners passing through the margins of the front flap between the said upper edge and said slit, and through the card body and rear flap, for closing the ends of the pocket.

5. An index device comprising a card having an integral tab projecting above the card body, a transparent sheath folded over the card tab to form front and rear flaps, the rear flap being secured upon the rear face of the tab and the front flap having its upper portion free from the tab surface to provide a label-receiving pocket and having a horizontal slit adjacent the bottom of the pocket to permit the insertion of a label, the portion of said front flap below said slit being secured flatwise upon the card body, said slit being spaced below the upper edge of the card body, and the sheath material at the ends of the slit being 70 bent to provide resilient shoulders, and fastening devices disposed between said upper edge and said shoulders, respectively, and adapted to depress the margins of the free 75 upper portion of the front flap upon the surface of the card.

Signed by me at Boston, Massachusetts this twenty-third day of January, 1928.

GEORGE H. DAWSON.
